JOSEPH E. CONNOLLY, OF NEWARK, NEW JERSEY.

KNOCKDOWN PAINTER'S SWINGING SCAFFOLD.

1,360,724.

Specification of Letters Patent. Patented Nov. 30, 1920.

Application filed February 26, 1920. Serial No. 361,539.

To all whom it may concern:

Be it known that I, JOSEPH E. CONNOLLY, a citizen of the United States, residing at Newark, in the county of Essex and State 5 of New Jersey, have invented certain new and useful Improvements in Knockdown Painters' Swinging Scaffolds; and I do hereby declare the following to be a full, clear, and exact description of the invention, 10 such as will enable others skilled in the art to which it appertains to make and use the same, reference being had to the accompanying drawings, and to characters of reference marked thereon, which form a part 15 of this specification.

The present invention relates, generally, to improvements in knock-down or take-apart scaffolds; and the invention has reference, more particularly, to a novel construction of knock-down painter's swinging scaffold for outside use upon the exterior 20 of buildings and other structures.

The invention has for its principal object to provide a painter's swinging scaffold 25 comprising a plurality of separable sections, so arranged that the same may be taken apart to render the scaffold more easily handled and carried from place to place, and at the same time more compact when so taken 30 apart so that the same may be conveniently loaded upon wagons, automobiles and the like, and also stored away in comparatively small space when not in use.

A further object of the present invention is 35 to provide a knock-down swinging scaffold, the sections of which are provided with exceedingly strong and reliable means for coupling the said sections together for use as a complete swinging scaffold, so that the same 40 may be rendered unquestionably safe to support the weight to be sustained thereby when in use, and may be used by painters and others with perfect confidence.

Other objects of the present invention, not 45 at this time more particularly enumerated, will be clearly understood from the following detailed description of the same.

With the various objects of the present invention in view, the same consists, primarily, in the novel knock-down swinging scaffold hereinafter set forth; and, the invention consists, furthermore, in the novel arrangements and combinations of the various devices and parts, as well as in the details of the construction of the same, all of 55 which will be hereinafter more fully de-

scribed, and then finally embodied in the claims appended hereto.

The invention is clearly illustrated in the accompanying drawings, in which:—

Figure 1 is a side elevation of my novel construction of knock-down scaffold with its separable sections operatively coupled together ready for use; Fig. 2 is a plan view of the same; Fig. 3 is a side elevation of the same showing the separable sections thereof in uncoupled relation permitting the scaffold to be knocked down or taken apart to render the same more easily portable; Fig. 4 is a detail cross-section taken on line 4—4 in said Fig. 1, the same being drawn on an enlarged scale; and Fig. 5 is another detail cross-section taken on line 5—5 in said Fig. 1, said view being also drawn on an enlarged scale.

Similar characters of reference are employed in all of the hereinabove described views, to indicate corresponding parts.

Referring now to said drawings the reference-character 1 indicates the complete knock-down scaffold made according to and embodying the principles of my present invention, the same comprising a plurality of separable sections, each comprising a pair of laterally spaced longitudinal side rails 2, 80 interconnected by lateral cross-bars 3 suitably secured thereto, said cross-bars 3 serving to support the flooring or platform strips 4. Preferably I employ three separable sections of suitable lengths, so that 85 when the same are coupled together they will provide a complete scaffold of the length desired, although it will be understood that the principles of my invention may be applied to scaffolds comprised of 90 two or more separable sections as may be found desirable.

The adjoining or abutting ends of the respective sections are provided, upon the upper and lower surfaces of the side rails 2 100 with straps or coupling bars 5, having at their outer ends outwardly extending perforate ears or lugs 6 projecting at right angles to the bodies of said straps or coupling bars 5, and having their outer faces flush with the ends of said side rails 2. Said straps or coupling bars 5 are secured to said side rails 2 by bolts, 7, which extend downwardly through the upper strap or coupling bar, and thence downwardly through the 105 body of said side rails 2 to extend through the lower strap or coupling bar, nuts 8 be-

ing engaged with the free outwardly projecting ends of said bolts for securing the described parts together. In the arrangement of three separable scaffold sections 5 illustrated in the drawings, said arrangement of straps or coupling bars 5 are provided at each end of the central or intermediate section, and at the inner ends of the respective outer sections.

10 Arranged in connection with the outer side faces of said side rails 2 of the respective outer sections, at their inner or abutting ends, are reinforcing plates 9, so disposed as to provide a longitudinally extending free end portion providing a tongue or interlocking member 10 projecting beyond the inner ends of said respective outer sections at each side thereof. Said reinforcing plates are secured to said side rails 2 by 15 bolts 11 which extend through said plates and transversely through said side rails 2 to project beyond the inner side faces of the latter, nuts 12 being engaged upon the free ends of said bolts to secure the same in 20 place.

Connected with the outer side faces of the said side rails 2 of said intermediate or central section, so as to project laterally outward therefrom adjacent to the ends of 30 said section, are pairs of yoke members 13 providing receiving sockets 14, adapted to receive and embrace said tongues or interlocking members 10 when the outer scaffold sections are properly assembled in connected 35 relation to said central or intermediate scaffold section. The lateral arms 15 of said yoke member 13 respectively extend laterally over the upper and lower surfaces of said side rails 2, being countersunk in said 40 side rails so as to be flush with said upper and lower surfaces thereof, and so as to be permitted to extend beneath the straps or coupling bars 5, and so disposed as to permit the bolts 7 to pass through both said 45 straps or coupling bars 5 and said lateral arms 15, whereby the latter as well as the former are securely fastened in proper positions to the side bars 2 by said bolts 7 and their nuts 8.

50 When it is desired to interconnect the said separable sections together to provide a complete scaffold, the outer end sections are brought into alignment respectively with the opposite ends of the intermediate section, 55 thus alining said tongues or interlocking members 10 of said reinforcing plates 9 with the receiving sockets 14 of the yoke-members 13, and the said outer sections are then pushed longitudinally inward to cause 60 the inner ends of their side rails 2 to abut the respective ends of the side rails of said central or intermediate section, and said tongues or interlocking members 10 to enter said receiving sockets 14 to be thus embraced 65 by said yoke members 13. When the side

rails 2 of the respective outer and central scaffold sections are thus brought into mutual abutting relation, the perforate ears or lugs 6 of the straps or coupling bars of adjoining sections, are alined together so 70 that a fastening bolt 16 may be passed through each pair of registered ears or lugs 6, and secured with a nut 17, thus binding said ears or lugs 6 together, and consequently firmly and efficiently mutually securing 75 together said several scaffold sections in operative coupled relation, and held against any possibility of accidental longitudinal separation one from the other. The tongues or interlocking members 10 of the outer scaffold sections being firmly embraced and engaged by the yoke-members 13 of the central or intermediate scaffold section, the said interconnected sections are securely braced at 80 their points of mutual interconnection against collapse, and are consequently rendered adequately strong and safe for the support of workman and materials when the scaffold is put into use.

90 In order to provide a further insurance against any possible accidental longitudinal separation of the several scaffold sections, when the same are arranged and secured in operative interconnected relation one to the other, I provide in one of each pair of the yoke-members 13 an opening or perforation 18, which is alined with a transverse opening or perforation 19 provided in the each side rail 2 of the central scaffold section. In like manner a similar opening or perforation 20 is provided in each tongue or interlocking member 10, so positioned that when the latter has been moved into operative embraced relation to the yoke 100 members 13, said opening or perforation 20 will aline itself with and intermediate of the respective openings or perforations 18 and 19, whereupon a transvere removable lock pin 21 may be thrust through the alined 110 openings, thus securing said tongues or interlocking members against withdrawal from the embrace of said yoke-members 13. Said lock pins 21 may themselves be secured 115 against accidental displacement by passing through their free ends, which project beyond the inner side faces of the side rails 2 of said central scaffold section, cotter-pins 22 or any other suitable fastening means 120 capable of being released when it is desired to withdraw said lock-pins.

125 It will be understood from the above description that I have provided a very simple easily manipulated, and yet exceedingly strong and efficient arrangement of devices for coupling and securing together in proper end to end arrangement, the several separable sections of a knock-down painter's or builder's scaffold, so that when in interconnected arrangement the complete 130

scaffold is of adequate strength for outside work, and perfectly safe in every way so that workmen may use the same at all levels of building exteriors with all confidence.

5 I am aware that some changes may be made in the arrangements and combinations of the various devices and parts, as well as in the details of the construction of the same, without departing from the scope of 10 my present invention as set forth in the foregoing specification and as defined in the appended claims. Hence, I do not limit my invention to the exact arrangements and combinations of the various parts as described in 15 said specification, nor do I confine myself to the exact details of the construction of the said parts as illustrated in the accompanying drawings.

I claim:—

20 1. A knock-down scaffold comprising a plurality of separable scaffold sections, coupling bars having up-turned perforate lugs at the abutting ends of adjoining sections, bolt and nut devices engaged through opposed lugs of said coupling bars to secure 25 said sections against longitudinal separation when assembled end to end, reinforcing plates providing longitudinal interlocking members secured to the sides of and projecting 30 beyond the abutting end of one section, and laterally projecting yoke-members secured to the sides of the abutting end of the adjoining section within the embrace of which said interlocking members are received 35 to reinforce the joined sections against collapse.

2. A knock-down scaffold comprising a plurality of separable scaffold sections, coupling bars having up-turned perforate lugs 40 at the abutting ends of adjoining sections, bolt and nut devices engaged through opposed lugs of said coupling bars to secure said sections against longitudinal separation when assembled end to end, reinforcing 45 plates providing longitudinal interlocking members secured to the sides of and projecting beyond the abutting end of one section, laterally projecting yoke-members secured to the sides of the abutting end of the adjoining 50 section within the embrace of which said interlocking members are received to reinforce the joined sections against collapse, certain of said yoke-members and said interlocking members having perforations 55 adapted to register in mutual alinement when said parts are operatively interconnected, and a removable transverse lock pin 60 for insertion through said alined perforations.

60 3. A knock-down scaffold comprising a plurality of separable scaffold sections, each scaffold section comprising a pair of laterally spaced longitudinal side rails, laterally extending cross-bars interconnecting said side 65 rails, and longitudinal flooring members sup-

ported upon said cross-bars intermediate said side rails; coupling bars secured to the upper and lower surfaces of the side rails at the abutting ends of adjoining sections, said coupling bars having upturned perforate 70 lugs at their outer ends extending flush with the abutting ends of said side rails, bolt and nut devices engaged through opposed lugs of said coupling bars to hold said sections against longitudinal separation when assembled end to end; reinforcing plates secured to the outer side faces of the side rails at the abutting end of one section, said reinforcing plates providing longitudinally extending interlocking members projecting 75 beyond said abutting end of one section, and laterally projecting yoke-members secured to the outer side faces of the side rails at the abutting end of an adjoining section within the embrace of which said interlocking members are received to reinforce the joined sections against collapse.

4. A knock-down scaffold comprising a plurality of separable scaffold sections, each scaffold section comprising a pair of laterally spaced longitudinal side rails, laterally extending cross-bars interconnecting said side rails, and longitudinal flooring members supported upon said cross-bars intermediate said side rails; coupling bars secured to the upper and lower surfaces of the side rails at the abutting ends of adjoining sections, said coupling bars having upturned perforate lugs at their outer ends 90 extending flush with the abutting ends of said side rails, bolt and nut devices engaged through opposed lugs of said coupling bars to hold said sections against longitudinal separation when assembled end to end; reinforcing plates secured to the outer side faces of the side rails at the abutting end of one section, said reinforcing plates providing longitudinally extending interlocking members projecting beyond said abutting end of one section, laterally projecting yoke-members secured to the outer side faces of the side rails at the abutting end of an adjoining section within the embrace of which said interlocking members are received to reinforce the joined sections against collapse. 95

5. A knock-down scaffold comprising a plurality of separable scaffold sections, fastening means for securing said scaffold sections together in end to end relation and held against longitudinal separation, reinforcing plates secured to the outer sides of and projecting beyond the abutting end of one section to provide interlocking mem- 100 105 110 115 120 125 130

bers, and laterally projecting yoke-members secured to the sides of the abutting end of the adjoining section within the embrace of which said interlocking members are received to reinforce the joined sections against collapse.

6. A knock-down scaffold comprising a plurality of separable scaffold sections, fastening means for securing said scaffold sections together in end to end relation and held against longitudinal separation, reinforcing plates secured to the outer sides of and projecting beyond the abutting end of one section to provide interlocking members, laterally projecting yoke-members secured to the sides of the abutting end of the adjoining section within the embrace of which said interlocking members are received to reinforce the joined sections against collapse, certain of said yoke-members and said interlocking members having perforations adapted to register in mutual alinement when said parts are operatively interconnected, and a removable transverse lock pin for insertion through said aligned perforations.

7. A knock-down scaffold comprising a plurality of separable sections adapted to be assembled end to end, reinforcing plates secured on opposite sides at the abutting end of one section, said reinforcing plates providing longitudinally extending interlocking members projecting beyond said abut-

ting end of said section, laterally projecting yoke-members secured to opposite sides at the abutting end of an adjoining section within the embrace of which said interlocking members are received, and means for preventing withdrawal of said interlocking members from operative engaged relation to said yoke-members.

8. A knock-down scaffold comprising a plurality of separable sections adapted to be assembled end to end, reinforcing plates secured on opposite sides at the abutting end of one section, said reinforcing plates providing longitudinally extending interlocking members projecting beyond said abutting end of said section, laterally projecting yoke-members secured to opposite sides at the abutting end of an adjoining section within the embrace of which said interlocking members are received, certain of said yoke-members and said interlocking members having perforations adapted to register in mutual alinement when said parts are operatively interconnected, and a removable transverse lock pin for insertion through said aligned perforations.

In testimony, that I claim the invention set forth above I have hereunto set my hand this 17th day of February, 1920.

JOSEPH E. CONNOLLY.
